UNITED STATES PATENT OFFICE.

CHARLES H. FRYE, OF SOUTH BEND, INDIANA.

SAFETY-RAZOR.

1,164,341.

Specification of Letters Patent. Patented Dec. 14, 1915.

Application filed May 21, 1914. Serial No. 840,087.

To all whom it may concern:

Be it known that I, CHARLES H. FRYE, a citizen of the United States, residing at South Bend, in the county of St. Joseph, 5 State of Indiana, have invented certain new and useful Improvements in Safety-Razors, of which the following is a specification.

The present invention has reference to safety razors, and more particularly to that 10 style or type of razor in which the handle and blade-holder are disposed approximately in alinement with, instead of at right-angles to, each other. It proposes certain hereinafter-described improvements in or relating to the construction of the two members or elements specified, whereby the implement, as a whole, is simplified and rendered less expensive to manufacture, while 15 at the same time, it offers a firmer and more 20 effective grip.

Also, the invention comprehends an improved form of clip which may be readily applied to or removed from the holder and which, when in place, will serve to accurately position the blade upon the holder 25 and retain it against movement when in use.

An embodiment of the invention is illustrated in the accompanying drawing, whereof:—

30 Figure 1 is a perspective view of the razor complete; Fig. 2 is an enlarged, fragmental longitudinal section on line 2—2, Fig. 1; Figs. 3 and 4 are transverse sections on lines 3—3, and 4—4, Fig. 2, respectively; and 35 Fig. 5 is a plan view of the blade.

In said drawing, 5 and 6 indicate the handle and holder members of the razor, and 40 7 the blade, the part last mentioned being of the well-known, double-edged, wafer type. The parts 5 and 6 are arranged substantially in alinement with each other, as shown, and are preferably integrally connected; they 45 may be constructed from any suitable spring metal and made in any desired sizes.

45 The handle element is so shaped as to enable it to offer an improved grip, as has already been stated, and it is further shaped in such a way as to enable it to be used with equal facility with either hand. To this 50 end, it is formed with an elongated, outer terminal portion or heel 5', the longitudinal edges of which have an inward curvature as they approach the point where the said heel joins the body of the holder, and at that 55 point the holder body is enlarged or widened

laterally in opposite directions to produce the finger-pieces 5''. Beyond said finger-pieces, the holder is provided at opposite edges with further enlargements 5''', which are in the form of wings or flaps, and these, 60 in turn, are rolled or bent over toward each other, so as to unite in constituting a rest or barrel over which the ends of the first and second fingers are curled when the implement is in use. The rear edges of the finger-pieces, (i. e., those adjacent the heel 5'), are 65 likewise concaved, or curved inwardly, and constitute continuations of the corresponding heel edges, thus conforming, somewhat, to the shape of the finger pressed there- 70 against, while the front edges of said finger-pieces are convexed, or outwardly curved.

Beyond the barrel 5''', the handle and holder are connected together by the flat, intermediate part 6' which occupies the plane 75 of the central or body portion 6'' of the holder and forms a continuation thereof. The said holder is provided at its opposite edges with longitudinal series of teeth 6'' which act in the usual way as the guards, 80 and are given a slight inclination, as shown in Figs. 3 and 4. The wafer blade 7 is disposed against the holder, and is of sufficient width to enable its edges to project past the bases of the teeth, its retention being effected 85 by means of spurs 6'' that are struck up from the enlarged end teeth of both series and are engageable in notches 7' formed in the end edges of the blade.

To secure the blade to the holder, there is 90 preferably employed a spring metal clip 8, which, in the construction illustrated, comprises a straight, or strip-like body portion 8' and a terminal hook 8'', the former being arranged against the front face of 95 the blade and the latter designed to fit over the back of the holder, as depicted in Figs. 1 and 2. The clip body 8' is sufficiently long to project beyond the rear end of the holder and across the connecting 100 portion or extension 6', while its width is such as to enable it to fit between the pairs of spurs 6''. The aforesaid extension 6' is formed upon its opposite edges with forwardly and inwardly bent tongues 6'', which 105 thus engage the projecting end of the clip body and, by reason of their inherent resiliency, exert a clamping pressure thereon, a similar action being exerted by the hook 8'' against the holder.

From the foregoing, it will be apparent that the clip can be readily and quickly inserted in, or withdrawn from, position by a single movement, and, when in position, will 5 be effectively held against displacement by means of its spring hook 8², and of the engagement of its rear terminal by the spring tongues 6⁶, while the clip itself will serve to retain the blade in position, being assisted to 10 this end by the engagement of the spurs 6⁴ in its notches 7'. The integral connection of the holder and handle elements enables them to be constructed from a single blank of metal and at a single operation of the 15 stamping or other press, thus reducing the cost of manufacture to a very considerable extent, while the particular shapes given the component members of the said handle enable the latter to fit either hand of the user 20 and, consequently, to afford a most satisfactory grip.

Having fully described my invention, I claim:—

A safety razor comprising integrally-connected holder and handle elements arranged 25 in axial alinement, said holder being provided adjacent its ends with pairs of spurs; a blade arranged against said holder and having notches in its end edges adjacent the corners thereof to receive said spurs; and a 30 clip arranged against the front face of the blade and removably engaged at opposite ends with said holder for retaining said blade in place.

In testimony whereof I have hereunto set 35 my hand in presence of two subscribing witnesses.

CHARLES H. FRYE.
